DESIGN FOR AN ASH TRAY

Lanny Grey, New York, N. Y.

Application September 25, 1946, Serial No. 133,552

Term of patent 14 years

(Cl. D85—2)

To all whom it may concern:

Be it known that I, Lanny Grey, a citizen of the United States, residing at New York, in the county of New York and State of New York, have invented a new, original, and ornamental Design for an Ash Tray, of which the following is a specification, reference being had to the accompanying drawing, forming a part thereof.

In the drawing:

Fig. 1 is a front perspective view of an ash tray, showing my new design;

Fig. 2 is a side elevational view;

Fig. 3 is a rear elevational view; and

Fig. 4 is another end elevational view of the same looking in the opposite direction of Fig. 2.

I claim:

The ornamental design for an ash tray, as shown.

LANNY GREY.
